SPOOL WINDING MACHINE

William F. Widman, Baltimore, Md., assignor to
 F. A. Lazenby & Company, Inc., Baltimore, Md.,
 a corporation of Maryland

Application October 8, 1933, Serial No. 234,009

18 Claims. (Cl. 242—18)

This invention relates, generally, to textile machinery and, more particularly, to apparatus for winding yarn on spools.

It is an object of this invention to provide a new and improved driving means for spools which are being wound, in which means the spool is driven from a rotating shaft or wheel through an intermediate drive roll which engages both the driving shaft for wheel and the spool which is being wound. In connection with this feature, it is another object of the invention to so adjust the forces between the primary and intermediate driving members and the driven spool that the engaging force between the primary driving member and the intermediate member will be less than the engaging force between the intermediate member and the driven spool, whereby any snarling or other stopping of the yarn fed to the spool will result only in slippage between the two driving members and not between the intermediate driving member and the spool, thereby preventing burning of the yarn on the spool.

An object of the invention is to provide driving means for spools which are to be wound, which means are so constructed and arranged that they may be brought manually and gradually into engagement with the spool to effect a controlled starting of the spool, after which weight means are brought into operation to continuously urge and maintain the driving means in driving relation with the spool.

Another object of the invention is to provide means for automatically removing the driving means from driving engagement with the spool, to thereby stop the rotation of the spool, which means will be made operative when the spool is fully wound to the outer peripheries of the side walls thereof, and regardless of the diameter of the spool.

A further object is to provide means for automatically removing the driving means from driving engagement with the spool, to thereby stop the rotation of the spool, which means will be made operative when the spool is partially filled to any pre-determined extent.

A still further object is to provide means which will move the spool from the winding position to a position in which it may be doffed, such means being made operable by the removal of the driving means from engagement with the spool.

A still further object is to provide means which will be operative to stop the rotation of the spool and to move it to doffing position immediately upon any breaking of the yarn being fed to the

spool, or upon the exhaustion of the yarn being fed to the spool.

A still further object is to provide means controlled by the tension of the yarn being fed to the spool and operative, when such tension is sufficiently great, to maintain the driving means in engagement with the spool, but which are operative, when the tension of the yarn falls below a pre-determined value to remove the driving means from the spool and move the spool to doffing position.

Other objects and features of novelty of the invention will be made apparent by the following description and the annexed drawings, it being understood, however, that such description and drawings are merely illustrative of the invention, which is not in any way limited thereby or otherwise than by the appended claims.

Referring to the drawings, in which similar reference numerals refer to like parts:

Fig. 1 is a side view showing mechanism according to the present invention;

Fig. 2 is a perspective view illustrating parts of the invention;

Fig. 3 is a top plan view of the mechanism illustrated in Fig. 1, and

Fig. 4 is a perspective view of the invention, certain parts thereof being omitted.

By the present invention there is provided a new and improved mechanism which is intended for use in the winding of yarn, string, thread or the like on a spool which is rotated in order to wind the yarn or other material thereon. This mechanism is operative to (1) cause the rotation of the spool to be started slowly under the full control of the operator to gradually bring it up to speed, weight means being then brought into operation to constantly maintain the driving means in engagement with the spool or the yarn thereon; (2) effect the rotation of the spool by the driving force of a rotating intermediate driving roll which is frictionally driven by a constantly rotating driving shaft or wheel; (3) cause slippage to occur between the primary and intermediate driving members in the event of snarling or other stopping of the yarn fed to the spool, rather than between the intermediate roll and the yarn wound on the spool, thus preventing burning of the yarn; (4) effect the automatic stopping and movement of the spool to doffing position when it is fully wound, this occurring regardless of the diameter of the side walls of the spool; (5) effect the automatic stopping and movement of the spool to doffing position when it has been filled to any pre-determined degree or

point; and (6) effect the stopping of the rotation of the spool and the movement of the spool to doffing position immediately upon the breaking of the yarn being fed to the spool or the exhaustion of the supply thereof. The means for effecting these new and useful results are illustrated in the drawings and reference is made to such drawings and to the following description for a full and complete understanding of the invention.

10 *Spool driving means*

A main driving wheel A is keyed to a shaft 1 and is constantly driven thereby and is frictionally engaged at its periphery with the periphery 15 of an intermediate drive roll 2 to constantly drive the same. The intermediate roll 2 is journaled on a shaft 4 which is disposed above and in parallelism with shaft 1 and slidably carried in the arms 3, 3 of a frame which pivotally carried by 20 shaft 1. The arms 3, 3 are disposed, respectively, on the opposite sides of the members A and 2, and a spring 5 attached to a connection 6 between the lower ends of the arms constantly urges the frame to vertical position as illustrated in Fig. 1. 25 Springs 7 are disposed between the shaft 4 and lateral extensions on the upper end of the frame and constantly urge the roll 2 into frictional engagement with the driving wheel A. It will be apparent that the frictional driving connection 30 between the members A and 2 will be maintained regardless of the angular disposition of the frame due to the pivotal mounting of the frame on the shaft.

35 Journalled in suitable bearings carried by fixed parts of the frame of the machine is a vertical, rotatable shaft 8, to the lower end of which there is rigidly attached, by suitable means, a horizontal spindle 9 upon which a spool may be received. The parts are so proportioned and 40 disposed that the spindle 9 may be moved from a doffing position, in which a spool may be placed thereon or removed therefrom, to a winding position in which the spindle is parallel to the shafts 1 and 4 and disposed forwardly thereof 45 at about the level of the shaft 4, all as clearly illustrated in Fig. 1. Means, to be described fully hereinafter, are provided by the invention for releasably latching the spindle 9 in winding position and for automatically moving it to 50 doffing position when the spool carried thereby is fully wound.

The intermediate drive roll 2 is of such thickness that it will be received between the end walls of a standard spool mounted on the spindle 9, when the spindle is in winding position, whereby when the intermediate drive roll is moved into engagement with the spool or with the yarn wound thereon the rotary movement thereof will be transmitted to the spool. It will 55 be seen that if the intermediate roll is disposed between the end walls of the spool and with its periphery in engagement with the yarn on the spool, the filling of the spool by the winding of the yarn thereon will move the roll and the 60 frame 3, 3 carrying the same away from the spindle 9. This movement of the frame 3, 3 and the intermediate roll is employed in the present invention to effect the automatic doffing of the spool.

70 The springs 7 which maintain the driving engagement between the intermediate drive roll and the main driving wheel are so adjusted that the friction between these two members is less than the friction between the intermediate roll and 75 the spool due to the means which urge the in-

termediate roll into engagement with the spool whereby, if there is any snarling of the yarn fed to the spool, slippage will occur between the main driving wheel and the intermediate roll rather than between the intermediate roll and the spool, thus preventing burning of the yarn by rotation of the intermediate roll against the 5 yarn.

Automatic movement of spool to doffing position 10

The vertical shaft 8 which carries the spindle 9 is surrounded by a spring 10 which constantly urges the shaft and spindle to the open or doffing position of the spindle, as illustrated in Fig. 4. The shaft and spindle may be rotated about the 15 vertical axis of the shaft 8, against the force of the spring 10, to the closed or winding position of the spindle, as illustrated in Fig. 3, in which the free end of the spindle is received within an open aperture 11 which is formed in a part 12a 20 of the fixed frame of the machine. When disposed in such position, with its free end in the aperture 11, the spindle is in position to permit a spool mounted thereon to be engaged by the 25 intermediate drive roll and wound.

Means are provided by the invention for holding the spindle in winding position until fully loaded and then releasing it from the aperture 11 and causing it to move automatically to doffing position. Such means comprise a latch 12 30 which comprises a vertical portion 13, which is pivotally connected at its upper end to the frame 12a of the machine, and a forwardly-extending latch portion 14 at the upper end of the vertical portion, a spring 15 being connected between the 35 lower end of the vertical portion and the frame in order to urge the latch to a position in which the latch portion thereof will be maintained in upper or operative position, although this same effect may be secured by providing a rearwardly- 40 extending weight portion at the lower end of the vertical portion. The latch portion 14 is provided in its upper surface with a notch or aperture 16 which surrounds the end of the spindle 9 when the same is in the aperture 11, to thereby 45 prevent movement of the end of the spindle out of the aperture 11, and the forward end of the latch portion is downwardly curved to permit the spindle, when swung into the aperture 11, to ride over and depress the latch portion. It will 50 be apparent that, in normal position and operation, the spring 15, or the weight portion of the latch, will maintain the latch portion thereof in raised position, in which the walls of the aperture 16 will prevent movement of the spindle out 55 of the aperture 11.

Extending between the frame 3, 3 and the latch 12 is a link or doffing bar 20 which is operative to transmit movement of the frame to the latch to cause the latch to be moved, at predetermined times, to such a position that the spindle will be released from aperture 11. At one end thereof the bar 20 has a lost motion connection to the frame 3, 3 through an elongated aperture 21 formed in the bar and which receives a pin carried by the frame. At its other end the bar has a lost motion connection with the latch through an L-shaped aperture 22 in the bar which receives a pin carried by the latch below the pivoted support therefor. The lost motion connections are so arranged that when the frame is in vertical position, its movement toward the spindle will first completely take up the lost motion between the frame and the bar by movement of the frame-carried pin along the 70 75

aperture 21 in the bar, after which the bar will be moved, by movement of the frame, to take up the lost motion between the latch and the bar. At the end of this second phase of the motion 5 the pin carried by the latch is received within the upwardly-extending recess forming part of the L-shaped aperture 22 in the bar. The connections between the frame and bar are now such that any movement of the frame away from 10 the spindle will first take up the lost motion between the frame and the bar, whereupon any further movement of the frame will cause the bar itself to move in the same direction. Such movement of the bar will cause a force to be immediately exerted on the latch tending to move 15 the same in a clockwise direction about its pivotal support, thereby moving the aperture 16 in the latch portion thereof out of locking engagement with the end of the spindle. The release 20 of the spindle will permit the spring 10 to rotate the shaft 8 in such a way as to move the end of the spindle 9 out of the aperture 11 and into a dawning position. Further movement of the frame 3, 3 toward vertical position by action of 25 the spring 5 will cause the upwardly-extending recess in the aperture 22 in the latch end of bar 20 to move out of engagement with the pin carried by the latch, thereby restoring the lost-motion connections to their normal position.

30 *Means for engaging the intermediate drive roll with the spool*

Means are provided by the invention for moving the intermediate drive roll from a released or 35 inoperative position into engagement with the spool which is to be loaded and for maintaining such driving engagement during the entire operation of loading the spool. Such means comprise a pair of arm 25 which are connected respectively to the opposite side of the frame 3, 3 40 and extend forwardly from the frame at points adjacent the pivotal support of the frame on the shaft 1. A rod 26 is carried by the free extremities of these arms and extends across the 45 face of the main driving pulley. An operating lever 27 is pivotally supported, intermediate its ends, on the rod 26 and the outer end of this lever is arranged to be grasped and manipulated by an operator. The inner end of the lever 27 is 50 pivotally connected, by a pivoted link 28, to a weight arm 29, the upper end of which is journaled about and supported by the shaft 1, and the lower end of which is normally supported by the frame member 30 adjacent an aperture 31 55 in the frame. A weight 32 is suspended from the lower end of the weight arm 29. Pivotally mounted intermediate its ends on the weight arm 29 is a latch lever 33, the lower end of which is constantly urged toward the lower end of the 60 weight arm by a spring 34. The intermediate portion of the upper arm of lever 33 is provided with a locking recess 35, which is adapted to receive a pin 36 which is carried by the upper end of one arm of a lever 37, which is pivotally mounted, intermediate its ends, on the end of rod 26 adjacent the operating lever 27, and the 65 lower arm 38 of which extends downwardly for a purpose to be described hereinafter.

In the operation of the described mechanism, 70 in order to engage the intermediate drive roll with a spool on spindle 9, the operator depresses the operating lever 27. During the first part of this movement the downward force on arm 27 will be exerted through rod 26 and arm 25 to cause the frame 3, 3 to move about its pivotal

support on shaft 1 from its vertical position toward the spool which is positioned on spindle 9. The operator thus moves the intermediate drive roll into driving engagement with the spool at a controlled rate, whereby the spool is gradually 5 brought up to speed, thus preventing any breaking of the yarn by reason of too quick starting of the spool. As the intermediate drive roll moves into engagement with the spool, the downward movement of the operating arm 27 will be resisted 10 and this arm will turn about its pivot on the rod 26, whereby any further downward movement of the operating arm will raise the inner end thereof. This movement of the inner end of the operating 15 lever will operate, through the link 28 to raise 16 the weight arm 29, the weight 32 and the latch lever 33, it being apparent that the operator is now supporting the weight 32 through the levers and linkages described. During the entire downward movement of the operating arm the pin 36, 20 which is carried by lever 37, is moved downwardly to such a position that when the operating arm is adjacent its lowermost position the pin 36 is opposite the locking recess 35 in the lever 33. Any further downward movement exerted by the 25 operator on the operating arm will cause the pin 36 to enter the recess. The downward force of the weight 32 is now applied through weight arm 29, latch lever 33, the locking notch in the latch lever, pin 36, lever 37, rod 26, and arms 25 to the 30 frame 3, 3, thereby exerting a force on the frame which tends to move the frame in a clockwise direction as viewed in Fig. 1 and constantly urging the intermediate drive roll into driving engagement with the hub of the spool on spindle 9 35 or with the yarn thereon.

Automatic stopping of spool when fully loaded

Means are provided by the invention for automatically stopping the rotation of the spool when 40 it is filled by yarn wound thereon, such means being operative regardless of the diameter of the spool. These means are clearly disclosed in Figs. 1 and 4 of the drawings and comprise a roller 50 which is carried at the extremity of a pivoted arm 45 51 and which is so disposed that it will be engaged by the periphery of one of the side walls of a spool which is in winding position on the spindle 9. The inner end of the arm 51 is sleeved about a shaft 52 and is connected thereto by a coil spring 53, such shaft having keyed thereto at one end a ratchet wheel 54, the toothed periphery of which is engaged by a pawl 55 which is normally urged into engagement with the toothed periphery of the ratchet by a spring 56 and which, 55 when engaged with the ratchet wheel prevents rotation of the ratchet, shaft 52 and the parts connected thereto, in a clockwise direction as viewed in Fig. 4. The pawl 55 is pivotally supported at its center and is provided with an end portion 63 which is disposed within the path of an abutment 64 carried by one of the arms 25. These parts are so proportioned and arranged that when the frame 3, 3 is moved to vertical position the abutment 64, which is rigidly attached thereto, is caused to strike the portion 63 of the pawl, thereby moving the pawl against the force of spring 56 in such a way about its pivot as to cause it to release the teeth of the ratchet wheel.

It will be seen that, due to the operation of the abutment 64, the pawl 55 will be disengaged from the ratchet wheel 54 at all times when the frame 3, 3 is vertical, and will engage the ratchet wheel only when the frame is in such position as 75

to drive a spool which is on the spindle. On the opposite end of the shaft 52 from ratchet wheel 54 there is keyed an arm 57, to the free extremity of which is pivotally connected the upper end of a downwardly-extending calibrating link 58, the lower end of which is supported by the free end of a calibrating lever arm 59, the other extremity of which is pivotally journaled on and supported by the shaft 1. A spring 66 is connected between the supporting arm 59 and the pivotal connection between the calibrating link 58 and arm 57 and operates to constantly urge the arm 51, shaft 52, ratchet wheel 54 and link 58 to normal or inoperative position.

15 The calibrating link 58 supports a pin 60 which is connected thereto in such a manner that it may be moved to a desired position along the link and retained there. In the construction disclosed, the link is provided with an elongated aperture 61 through which the shank of the pin 60 extends, a locking nut being provided for holding the pin in adjusted position along the aperture.

20 The pin 60 is disposed within the path of movement of the lower end 38 of the lever 37, and it will be apparent that when a spool is placed on the spindle 9, and the spindle moved to winding position, one of the side walls of the spool will engage the roller 50, moving the same, 25 the arm 51, shaft 52, arm 57, calibrating link 58, pin 60 and supporting arm 59 to a position determined by the radius of the end wall of the spool, whereby the pin 60 will assume a position in the path of lever arm 38 and spaced therefrom 30 a distance which is dependent upon the radius of the end wall of the spool.

35 As the yarn is wound on the spool, the intermediate drive roll, bearing as it does on the surface of the wound yarn, will be moved away from the spindle 9. This movement will cause the frame 3, 3 to move in a counterclockwise direction as viewed in Fig. 1, thus moving the arms 25, 25 in the same direction and raising the entire lever 37. The upward movement of lever 40 37 is transmitted to the weight 32 through the latch lever 33 and the weight arm 29, thus causing the weight to maintain the intermediate drive roll in driving engagement with the spool. 45 As the lever 37 is raised, the lower end 38 thereof will also be raised until it engages the pin 60, the position of which, as set forth hereinbefore, is determined by the radius of the end wall of the spool. After the lever arm 38 has engaged the pin 60 any further upward movement of the 50 lever arm will be resisted by the pin and such further movement will cause the lever 37 to rotate in a counter-clockwise direction about its pivotal connection to the operating lever 27 and the arms 25, thus moving the pin 36 out of engagement with the notch in the latch lever 33. It will be apparent that in order to effect the 55 described rotation of lever 37 the pin 60 must be held against any upward movement. The pin will be maintained in its set and predetermined position, and will resist any upward force exerted thereon by arm 38 of lever 37, by reason of the engagement of the pawl 55 with the ratchet wheel 54 which engagement, as described, prevents rotation of the ratchet wheel, shaft 52 and 60 connected parts in a clockwise direction as viewed in Fig. 4. The release of the engagement between the operating arm 27 and the weight arm 29, which results from the described action, causes the load of the weight 32 to be taken by 65 the weight arm 29 which again is brought to rest 70 75

on the frame member, as illustrated in Fig. 1. The disengagement of the parts of the latch means releases the force of the weight 32 from the lever 37, arms 25 and the frame 3, 3 and the spring 5, the force of which has heretofore been overcome by the oppositely-acting force of the weight, now operates to move the frame 3, 3 to vertical position, thereby moving the intermediate drive roll out of driving engagement with the spool or the yarn loaded thereon, and to also move the operating arm 27 to raised position.

75 The movement of the frame to its inoperative or vertical position, in the manner described, causes the operation of the latch 12 to release the spindle 9, all in the manner fully described hereinbefore, whereby the spool on spindle 9 is released from the aperture 16 and is automatically moved to doffing position by the spring 10.

80 It will be seen that, due to the fact that the position of pin 60 controls the release of the driving means from the spool and due to the further fact that the position of pin 60 is determined by the radius of an end wall of the spool, the release of the intermediate driving roll from the spool will be automatically effected upon the completion of the loading of the spool, to the limits of the end walls thereof, following which the spool will be immediately and automatically moved to doffing position.

85 When the spool is doffed it will, of course, be necessary to return the ratchet wheel and associated parts, including the pin 60, to normal, inoperative position in order to permit another spool to be loaded on the spindle 9. This is effected by spring 66 which constantly urges the 90 shaft 52, ratchet wheel 54 and arm 51 in a counter-clockwise direction as viewed in Fig. 4. It will be remembered that at this time the pawl 55 has been moved out of engagement with the ratchet wheel by the movement of frame 3, 3 to vertical position, thereby permitting the described operation.

Automatic stopping of spool when partially loaded

95 Means are provided by the invention for automatically removing the driving force from the spool when yarn has been wound on the spool to any predetermined extent which is less than full loading. Thus, it may be desired to wind the spool to only one-half its fully loaded capacity, or to some mark on the spool, and the means to be described will be operative to cause the driving means to be released from the spool, and the spool moved to doffing position when the 100 yarn has been wound on the spool to this predetermined extent or point.

105 Such means comprise an arm 70, one end of which is connected to the shaft 52 and the other end of which is provided with a lug 71 which extends through a curved aperture 72 in a plate 60 13 and is screw-threaded to receive a tightening nut 74. A scale is preferably provided adjacent the aperture 72 in order that the arm 70 may be moved to any desired predetermined position. As stated hereinbefore, the arm 51 is connected 65 to shaft 52 only by a spring 53 and, accordingly, the arm 51 and roller 50 may be moved to a position in which the roller will not be engaged by the end wall of a spool placed in loading position on the spindle 9, all without affecting in 70 any way the position of the shaft 52, ratchet wheel 54, pin 60 or other associated parts. A latch pin 75 is slidably mounted in the frame of the machine and is normally urged to an outer inoperative position by a spring 76. This pin 75

may be moved inwardly toward the arm 51, after such arm has been moved to the inoperative position described and will then be operative to engage and hold the arm in such inoperative position.

In the operation of the described structure, if it is desired to load a spool to only one-half of its capacity, the operator first moves arm 51 to its inoperative position, in which it will not engage the end wall of the spool to be loaded, and then locks the arm in such position by placing the pin 75 in the path of its return movement, as described. Such setting of the arm 51 will not affect the position of shaft 52, ratchet wheel 54 or pin 60 in any way. The arm 70 is now moved to the $\frac{1}{2}$ mark on the scale adjacent the aperture 72 and is locked in this position, thus rotating the shaft 52 to an extent and moving the pin 60 to a position determined by such setting of the arm 70. As described hereinbefore, the position of the pin 60 causes the automatic stopping and doffing of the spool, and these operations will accordingly be effected when the spool is loaded to one-half of its capacity.

25 *Means for stopping the spool and moving it to doffing position upon breaking of the yarn or exhaustion of the supply*

Means are provided by the invention for stopping the rotation of the spool upon breaking or exhaustion of the supply of the yarn which is being fed thereto. Such means are disclosed particularly in Figs. 1, 2 and 4 and comprise an arm 80 which is mounted to swing in a vertical plane about a pivotal connection between its upper end and the upper end of a pivoted member 81, the lower end of which is provided with a cam surface 82 which engages an oppositely-formed cam surface 83 on the upper end of the latch lever 33. Upon the lower end of arm 80 there is mounted a rod 84 which extends transversely across the face of a spool which is in loaded position on spindle 9. The yarn being fed from the skein (not shown) to the spool passes 45 below the rod 84 and the tension of the yarn holds the rod and the arm 80 in a raised position in which the lever is removed from the path of an abutment 85 which is carried by and moves with the traverse bar 86.

50 In the operation of the described means, so long as the yarn tension is sufficient to hold the arm 80 in raised position the abutment 85 will pass the arm freely during the movement of the traverse bar but, if the yarn breaks, the arm will 55 be permitted to fall into the path of the abutment. Upon being engaged by the abutment the arm will be moved in a direction parallel to the traverse bar and will thereby cause the lever 81, to which it is connected, to be moved about its 60 pivot thus causing the cam surface thereon to be moved across the cam surface on lever 33. The relative movement of the cam surfaces on the levers 81 and 33 will cause the lever 33 to be moved in such a way as to disengage the notch 65 therein from the pin 36 on the upper arm of lever 37, thereby disengaging the weight means from the operating arm 27 and the frame 33 and permitting the spring 5 to move the frame to its 70 vertical position, thereby moving the intermediate roll out of engagement with the spool.

The pivoted arm 80 is normally held in raised, or inoperative, position by the engagement of an extension member 100, which is pivotally supported on the lower end thereof, by an offset portion 75 101 of the operating lever 27. Thus, when

the operating lever is in its upper, inoperative position, it also maintains the arm 80 in raised position in which it is removed from the path of the abutment 85.

While I have illustrated and described one embodiment of my invention, it will be apparent to those skilled in the art that changes and improvements may be made therein and further modification thereof practised, all without departing in any way from the spirit or scope of the invention, for the limits of which reference must be had to the appended claims.

I claim:

1. Spool winding mechanism comprising a driving wheel, a spindle adapted to receive a spool 15 on which yarn is to be wound and to position such spool adjacent but out of contact with the driving wheel, an intermediate drive roll, means constantly urging the periphery of the intermediate drive roll into frictional engagement with 20 the periphery of the driving wheel, means normally operable to maintain the intermediate drive roll out of engagement with the spool on said spindle, and other means operable to overcome the action of said last named means to thereby 25 maintain the intermediate drive roll in driving engagement with the spool.

2. Spool winding mechanism comprising a driving wheel, a spindle adapted to receive a spool 30 on which yarn is to be wound and to position such spool adjacent but out of contact with the driving wheel, an intermediate drive roll, means constantly urging the intermediate drive roll into frictional peripheral engagement with 35 the periphery of the driving wheel, means normally operable to maintain the intermediate drive roll out of engagement with the spool, and means operable to overcome the action of said last named means and to maintain the intermediate drive roll in driving engagement with the spool, the means urging the intermediate drive roll and the driving wheel into frictional engagement being of less force than the means maintaining the intermediate drive roll in driving engagement 40 with the spool. 45

3. Spool winding mechanism comprising a driving wheel, a spindle adapted to receive a spool on which yarn is to be wound and to position such spool adjacent but out of contact with the driving wheel, a pivotally mounted frame, a drive 50 roll rotatably mounted in said frame and being positioned in constant frictional peripheral driving engagement with the driving wheel, means for varying the frictional engagement between the driving wheel and the roll mounted in the 55 frame, means for moving the frame to a position in which the roll carried thereby is in frictional peripheral driving engagement with the spool and with the driving wheel, means for releasably maintaining the frame in such position, and means constantly urging the frame to a position in which the roll carried thereby is out of engagement with the spool. 60

4. Spool winding mechanism comprising a driving wheel, a spindle adapted to receive a spool 65 on which yarn is to be wound and to position such spool adjacent but out of contact with the driving wheel, a pivotally mounted frame, a drive roll rotatably mounted in said frame and being in constant frictional peripheral driving 70 engagement with the driving wheel, means for varying the frictional engagement between the driving wheel and the roll mounted in the frame, means for moving the frame to a position in which the roll carried thereby is in frictional 75

peripheral driving engagement with the spool, weight means operable to releasably maintain the frame in such position, and spring means constantly urging the frame to a position in which 5 the pulley carried thereby is out of engagement with the spool.

5. Spool winding mechanism comprising a driving wheel, a spindle adapted to receive a spool on which yarn is to be wound and to position 10 such spool adjacent but out of contact with the driving wheel, a pivotally mounted frame, a drive roll rotatably mounted in said frame and being positioned in constant frictional peripheral driving engagement with the driving wheel, means 15 for varying the frictional engagement between the driving wheel and a roll mounted in the frame, means for moving the frame to a position in which the roll carried thereby is in frictional peripheral driving engagement with the driving 20 wheel and the spool, means for releasably maintaining the frame in such position, the parts being so adjusted that the frictional resistance between the driving wheel and the roll carried by the frame is less than the frictional resistance 25 between the roll carried by the frame and the spool caused by said maintaining means, and the first named frictional resistance is less than the strength of the yarn being wound on the spool.

6. Spool winding mechanism comprising a 30 spindle adapted to rotatably support a spool adapted to have yarn wound thereon, rotatable driving means movable into engagement with yarn wound on said spool and operable to cause the rotation thereof whereby the driving means 35 is moved away from the axis of the spool as the yarn is wound thereon, abutment means adapted to be operated by a spool placed on said spindle in position to have yarn wound thereon and movable to a position determined by the radius 40 of the side wall of such spool, and means operable to cause the driving means to be moved out of driving engagement with the yarn wound on the spool and which are movable with the driving means as such means move away from the axis 45 of the spool and which are operable upon engagement thereof with the abutment means.

7. Spool winding mechanism comprising a rotatably mounted spool adapted to have yarn wound thereon, rotatable driving means mounted 50 for movement into engagement with yarn wound on said spool and operable to cause the rotation thereof whereby said driving means is moved away from the axis of the spool as the yarn is wound thereon, abutment means movable to any 55 desired position, and means operable to cause the driving means to be moved out of driving engagement with the yarn wound on the spool, said means being movable by the driving means and into engagement with said abutment means as 60 the driving means move away from the axis of the spool and being operable by engagement thereof with the abutment means, whereby the driving means is moved out of driving engagement with the spool when the spool is loaded 65 to the desired degree determined by the predetermined setting of the abutment means.

8. Spool winding mechanism comprising a rotatably mounted spool, driving means engaging the yarn being wound on the spool and adapted 70 to rotate the spool and to be moved away from the axis of the spool as the spool is loaded, means movable with said driving means and being operable when in operative position to maintain the driving means in engagement with the spool, 75 means arranged in the path of movement of the

movable means and positioned with respect thereto in accordance with the radius of a side wall of the spool being loaded, said movable means being operable upon engagement thereof with the last-named means to release the driving means from driving engagement with the spool. 5

9. Spool winding mechanism comprising a rotatably mounted spool, a drive roll mounted for movement into and out of engagement with the yarn being wound on the spool, spring means 10 urging the drive roll out of engagement with the spool and weight means operable to urge the drive roll into engagement with the spool, a normally disengaged latch means operable to latched position in which the weight means causes 15 the drive roll to drivably engage the spool, said latch means having a portion movable with the drive roll as such roll is moved by the yarn loaded on the spool, an abutment arranged in the path of movement of said portion and operative by the 20 spool being loaded to a position in accordance with the radius of an end wall of the spool, said abutment being operable after engagement thereof by said portion of the latch means to cause disengagement of the latch means, whereby the 25 drive roll is released from driving engagement with the spool.

10. Spool winding mechanism comprising a rotatably mounted spool, a drive roll mounted for movement into and out of engagement with the 30 yarn being wound on the spool, spring means urging the drive roll out of engagement with the spool and weight means operable to urge the drive roll into engagement with the spool, a normally disengaged latch means having two parts, one of 35 which is connected to the drive roll and one of which is connected to the weight means, whereby when the latch means is in engaged position the weight means causes the said roll to drivably engage the spool, said latch means having a portion movable with the drive roll as such roll is moved by the yarn loaded on the spool, an abutment arranged in the path of movement of said portion and operative by the spool being loaded to a position in accordance with the radius of 40 an end wall of the spool, said abutment being operable, after engagement thereof by said portion of the latch means to cause disengagement of the latch means, whereby the drive roll is released from driving engagement with the spool. 45

11. Spool winding mechanism comprising a rotatably mounted spool, a drive roll mounted for movement into and out of engagement with the 50 yarn being wound on the spool, spring means urging the drive roll out of engagement with the spool and weight means operable to urge the driving pulley into engagement with the spool, a normally disengaged two-part latch means including one part which is connected to the weight means 55 and a second part which is connected to the drive roll, said second part comprising a pivoted lever one arm of which forms part of the latch means and the second arm of which moves with the drive roll and is operable when such movement is stopped to disengage the latch means, an abutment arranged in the path of movement of the second arm of said lever and being movable by the spool being loaded to a position dependent upon the radius of a wall of said spool, whereby said abutment will stop the aforesaid movement 60 of the second arm of said lever to thereby cause disconnection of the latch means when the spool has been fully loaded. 65

12. In spool winding mechanism, a horizontal spindle adapted to receive a spool which is to be 75

loaded, said spindle being movable about a vertical axis from a doffing position to a winding position, means constantly urging the spindle to doffing position, and releasable latch means operable to hold the spindle in winding position.

13. Spool winding mechanism comprising a horizontal spindle adapted to receive a spool upon which yarn is to be wound, said spindle being movable about a vertical axis from a doffing position to a winding position, means constantly urging the spindle to doffing position, means operable to releasably hold the spindle in winding position, driving means movable from an inoperative position to an operative position drivably engaging a spool on said spindle when the spindle is in winding position, and means operable by movement of the driving means to inoperative position for releasing the said holding means to thereby cause the spindle and the spool carried thereby to be moved to doffing position.

14. Spool winding mechanism comprising a horizontal spindle adapted to receive a spool upon which yarn is to be wound, said spindle being movable about a vertical axis from a doffing position to a winding position, means constantly urging the spindle to doffing position, latch means operable to releasably hold the spindle in winding position, driving means movable from an inoperative position to an operative position in which it drivably engages a spool on said spindle when the spindle is in winding position, and a connection between the driving means and the latch means which is so constructed and arranged as to freely permit the driving means to drivably engage a spool which is in winding position on the spindle and which operates the latch means to disengage the spindle when the driving means moves to inoperative position to thereby cause the spindle and the spool carried thereby to be moved to doffing position.

15. Spool winding mechanism comprising a main driving wheel, a rotatably mounted spool adjacent but out of engagement with said wheel, a frame pivoted at the axis of said wheel, an intermediate drive roll rotatably mounted in said frame and being so positioned that it is carried by movement of the frame from a position in which it is in frictional peripheral engagement only with the main wheel to a position in which it is in frictional peripheral engagement with both the main wheel and the spool to thereby cause rotation of the spool, an arm connected to the frame, an operating lever pivotally connected intermediate its ends to said arm and having an outer extremity providing a handle portion and an inner extremity connected to a weight, whereby initial movement of said lever in one direction will cause movement of the frame to cause the intermediate wheel to drivably engage the spool and subsequent movement of the lever will cause the force of the weight to be applied to the pivotal connection between the operating lever and the arm connected to the frame.

16. Spool winding mechanism comprising a

main driving wheel, a rotatably mounted spool adjacent but out of engagement with said wheel, a frame pivoted at the axis of said wheel, an intermediate drive roll rotatably mounted in said frame and being so positioned that it is carried by movement of the frame from a position in which it is in frictional peripheral engagement with the main driving wheel to a position in which it is in frictional peripheral engagement with the main driving wheel and the spool to thereby cause rotation of the spool, an arm connected to the frame, an operating lever pivotally connected intermediate its ends to said arm and having an outer extremity providing a handle portion and an inner extremity connected to a weight, whereby initial movement of said lever in one direction will cause movement of the frame to cause the intermediate drive roll to drivably engage the spool, a two part latch means having one portion thereof connected to said weight and another portion connected to the operating arm, said latch parts being so constructed and arranged as to become engaged upon movement of the operating lever after the engagement between the intermediate drive roll and the spool, whereby the force of the weight is caused to maintain the engagement between the intermediate drive roll and the spool.

17. Spool winding mechanism comprising a spool rotatably mounted and adapted to have yarn wound thereon, a rotatable drive roll mounted to drivably engage the spool, means constantly urging said roll into driving engagement with the spool, means operable to disconnect said means from the drive roll to thereby cause said roll to move out of driving relation with the spool, means operable by the yarn fed to the spool for preventing the operation of the last-named means while the yarn fed to the spool is under a pre-determined tension and operable when the tension falls below a predetermined value to cause the operation of said means to thereby move said drive roll out of driving engagement with the spool.

18. Spool winding mechanism comprising a spool rotatably mounted and adapted to have yarn wound thereon, a rotatable drive roll mounted to drivably engage the spool, means constantly urging said roll into driving engagement with the spool, means operable to disconnect said means from the drive roll to thereby cause said roll to move out of driving relation with the spool, a movable member, a lever which is operable by said movable member to cause the operation of the disconnecting means, said lever being so constructed and arranged that it is held out of the path of the movable member by the yarn fed to the spool so long as such yarn is under a pre-determined tension but is movable into operative position by breaking of the yarn or reduction of the tension thereof below the predetermined value.

WILLIAM F. WIDMAN.
